No. 890,154.

PATENTED JUNE 9, 1908.

J. G. MASTIN.
FIRE EXTINGUISHER.
APPLICATION FILED DEC. 23, 1907.

UNITED STATES PATENT OFFICE.

JAMES G. MASTIN, OF CHICAGO, ILLINOIS.

FIRE-EXTINGUISHER.

No. 890,154.

Specification of Letters Patent.

Patented June 9, 1908.

Application filed December 23, 1907. Serial No. 407,725.

To all whom it may concern:

Be it known that I, JAMES G. MASTIN, a citizen of the United States, residing at Chicago, in the county of Cook and State of Illinois, have invented certain new and useful Improvements in Fire-Extinguishers, of which the following is a specification.

This invention relates to certain new and useful improvements in fire extinguishers, and it has for its object the production of a device of this character which is simple in construction, cheap to manufacture and efficient for the purpose for which it is designed.

With these and other objects in view my invention consists in certain constructions, arrangements and combinations of parts the preferred form of which will be first described in connection with the accompanying drawings and then the invention particularly pointed out in the appended claims.

Referring to the drawings wherein the same part is designated by the same reference numeral wherever it occurs Figure 1 is a perspective view of a fire extinguisher; Fig. 2 is a central longitudinal section of the same, certain parts being shown in elevation; Fig. 3 is a detail perspective view of the cover plate with parts removed and Fig. 4 is a detail perspective view of the part which forms the exhaust tube of the pump.

1 designates the container or casing in the upper end of which is secured the ring 2. In the form of my invention shown, the ring is secured in the container by soldering the upper edge of the container into the groove 3 formed near the lower edge of the ring. The ring is provided with the outwardly projecting circumferential shoulder 4, formed with the cam surface 5, on its lower side, and on its upper side at the inner edge with the projecting bead 6.

7 designates the filler plug which is adapted to close the opening in the ring. This plug on its upper surface is provided with transversely extending ribs 8 which, at their ends, are provided with the openings 9, in which are mounted the pins 10 on which are journaled the locking levers 11. These levers are provided with handles 12 and the projecting cam portions 12' adapted to engage the cam surface 5 on the underside of the shoulder 4 to removably lock the filler plug in position.

The lower portion 13 of the filler plug loosely fits within the ring 2 while the main

portion thereof extends over the ring as shown.

14 is a circumferential channel cut in the reduced portion 13 in which a packing washer 15 of rubber or other suitable material is placed, the washer being securely held in position by the projecting ledge 16 on the lower side of the channel. It will be seen that when the plug is locked in position, as shown in Fig. 2, the bead 6 will be forced into the washer 15, thus compressing the body of the washer and forming a tight joint.

17 is the pump barrel which is provided with the usual piston 18 connected to the piston rod 19 having at its upper end the operating handle 20.

21 is a plate bent upward at right angles adjacent to each longitudinal edge, forming an E-shaped structure 22, which is secured to the side of the pump barrel as best shown in Fig. 2. This structure forms the exhaust tube for the pump, and at its upper and lower ends is closed by means of the caps 23. Near the lower end of the pump barrel provide an opening 24 extending therethrough and into the exhaust tube formed by the structure 22. Near the upper end of the structure 22 I provide an opening 24 through which air from the pump may pass out into the casing, the opening being provided with an ordinary flap valve 25 to prevent the air from within the casing being drawn into the pump barrel.

26 is a pipe passing through the upper portion of the casing 1 and extending down nearly to the bottom of the casing. This pipe, outside the casing, has connected thereto, a hose 27 provided on its outer end with a nozzle 28.

In the operation of my invention the container 1 is filled by removing the filling plug 7, which carries the pump and then filling the casing with fire extinguishing or other liquid. The pump is then inserted in the opening in the ring 3 and the filling plate 100 locked in position by pressing down the levers 11, causing the cam portion 12' to pass under the cam surface 5 on the lower side of the ring 2. This hermetically seals the filling plug in the ring. Upon operating the pump air is forced through the conduit formed by the structure 22 out through the opening 24 and into the casing during the down-stroke, while during the up-stroke of the piston the air is prevented from passing back into the pump.

barrel by the valve 24. Thus producing a pressure in the casing which will force the fire extinguishing or other liquid out through the nozzle.

5 While I have described what I believe to be the preferred form of my invention, I desire to have it understood that many changes may be made in the form, construction and arrangement of parts without departing from 10 the spirit thereof.

What I claim as new and desire to secure by Letters Patent is

1. In a fire extinguisher, the combination with a casing, of a pump comprising a barrel 15 and piston removably mounted within the casing, a tube formed by a sheet of metal bent longitudinally and attached at its lower edges to the sides of the pump barrel, said barrel being provided with an opening near its lower end which connects the 20 barrel and tube, said tube being provided with an opening near the top thereof and a valve for controlling the passage of air therethrough.
- 25 2. In a fire extinguisher, the combination with a casing, of a ring mounted upon the upper end of the casing and provided with an opening therethrough, a filler-plug, a pump

barrel centrally mounted in the filler-plug, said filler-plug being provided with a channel 30 in its lower portion, a rubber washer mounted in said channel, a circumferential shoulder on the ring, said shoulder being provided with a bead on its upper surface and on its lower side with a cam surface, and levers 35 pivoted to the filler plug and having engaging portions adapted to engage the cam shoulders to lock the filler-plug in position.

3. In a fire extinguisher the combination with a casing, of a pump comprising a barrel 40 and piston removably mounted in the casing, a tube formed by a sheet of metal bent longitudinally and attached at its lower edges to the sides of the pump barrel, said barrel being provided with an opening a short distance 45 above its lower end which connects the barrel and tube, said tube being provided with an opening near the top thereof, and a valve for controlling the passage of air therethrough. 50

In testimony whereof I affix my signature in presence of two witnesses.

JAMES G. MASTIN.
